UNITED STATES PATENT OFFICE.

LORENZ B. FUTER, OF GORDONVILLE, PENNSYLVANIA.

CATCHING AND DELIVERING MECHANISM FOR MAIL-BAGS.

No. 904,058.

Specification of Letters Patent.

Patented Nov. 17, 1908.

Application filed June 9, 1908. Serial No. 437,512.

To all whom it may concern:

Be it known that I, LORENZ B. FUTER, a citizen of the United States, residing at Gordonville, in the county of Lancaster and State of Pennsylvania, have invented certain new and useful Improvements in Catching and Delivering Mechanism for Mail-Bags, of which the following is a specification.

My invention relates to mail-bag catchers and deliverers, and particularly to those catchers which are mounted rotatably on a standard beside the track and have free rotation therearound to take up the shock caused by the impact of the bag, and to deliverers adapted to operate in conjunction therewith.

One object of my invention is to provide a catcher wherein the bag is received from a moving train without jar, and the rectilinear motion of the bag transformed into a circular motion about the axis of the catcher, the bag being locked on the catcher immediately upon its reception, so that no rebound will throw it out of the catcher, and so that it cannot be otherwise removed accidentally until the catcher comes to a stop and the gate thereon be manually opened to release the bag.

Another object of my invention is to provide a mechanism wherein the bag will not be subjected to such action as will tend to rend it open, or otherwise damage it and its contents.

To these ends my invention consists in a catching or receiving mechanism having a catching arm normally locked in its receiving position, but adapted to be unlocked when the mail-bag is received and to be freely rotated about a standard as a center, said arm being provided with a pivoted gate operating when the bag is caught to unlock the arm and to lock the bag upon the catching arm.

The invention also consists in the peculiarly shaped bag-anchor or support which is hung from the delivering mechanism and is engaged directly by the catching mechanism.

In the drawings, Figure 1, is a perspective view of my apparatus in use. Fig. 2, is a plan view of the catching or receiving arm. Fig. 3, is a vertical section of the receiving arm and connected mechanism, the gate being in elevation. Fig. 4, is a detail perspective of the bag supporting finger.

Fig. 5, is a detail of the bag-anchor or support.

The standard 2 upon which the receiving arm is mounted is located adjacent to the track and is provided at its upper end with the capital or enlarged head 3, which may be of any suitable form, but which should have a flat upper plate 3', forming a bearing for the arm 5. The under face of the arm 5 is flat and conforms to the upper surface of the plate 3'. Ball races are formed in the plate 3' and under face of the arm 5, in which are located the anti-friction balls 4. Preferably the head or capital 3 is hollow, and a headed bolt 7 passes upward through the upper plate 3' and the arm 5 to hold the arm upon the head 3. The bolt is provided with the nuts 7' and with the washer 8 supported upon the anti-friction balls 8'. These balls are mounted in race-ways formed on the under side of the washer 8 and the upper side of the arm 5. It will be seen that the arm 5 has free rotary motion around the bolt 7 as the axis, and that the arm is supported with as little friction as possible upon the head 3 of the standard 2. The arm 5 is pivoted about at its middle. One end is provided with the counterweights 9, which are adjustable along the arm as will be later described, and the other end is provided with the catching hook and gate mechanism into which the mail-bag or its supporter is received. Preferably I form the arm 5 relatively wide in order to give a firm support to the gate locking mechanism. At its end, the arm is formed into a hook 10, one side of which at its end is outwardly bent as at 10', so as to guide the bag-anchor or support into the body of the hook. Pivoted upon what may be called the forward edge of the arm 5, is the U-shaped gate 11 whose arms 11', 11'' when the gate is in the position shown in Fig. 1, are in alinement with the sides of the hook formed on the end of the arm 5. This gate when turned occupies the position shown in dotted lines Fig. 2, wherein the arms are transverse to the sides of the hook 10, and lie across said hook closing the same.

It will be seen that if the exterior arm 11' of the gate be omitted, the gate will have the shape of a bell-crank or angle lever in plan, one arm of which contacts with the bag or holder, the other closing the entrance

105

110

of the receiving hook after the bag holder has entered. The gate is pivoted eccentrically and not at its middle and is free to turn when struck, as by a mail-bag or the mail-bag support to be hereafter described. The gate will be thus turned from the position shown in Fig. 2 to the position shown in dotted lines, whereupon the arm 11" will close the hook 10 and securely hold the mail-bag within the closed hook. The arm 11" is outwardly inclined as shown, to more perfectly guide the bag holder into the opening of the gate.

While it is necessary that the receiving arm should be free to rotate until the shock of the bag impact has been taken up, yet it is also necessary that the arm should be held rigidly in its catching position when the train is approaching, so that it may have proper relative alinement with the delivering device on the train, and so that it may not be moved from that position by wind or otherwise. To this end I form the upper face of the plate 3' with a recess or notch 3" and provide the arm with a spring actuated pin 13 entering said recess when the arm is in the catching position, which pin is adapted to be raised when the mail-bag has been caught by the hook. To prevent the immediate rotation of the arm upon the bag being received before it is properly engaged in the hook, I provide a longitudinally extending spring rod 12, attached at one end in any suitable manner to the arm 5, preferably rearward of the axis of the arm, which rod carries projecting downward from it, the pin 13, which passes through an opening in the arm 5 and is adapted to enter the recess 3" in the plate 3'. The spring normally holds this pin in the recess 3", but in order that the pin may be lifted out of the recess, I extend the arm 12 forward and turn it upwardly. The rear edge of the gate plate 11 is wedge shaped or otherwise formed (see Fig. 1), so that as it is turned to the position shown in dotted lines, that is the locking position, it will wedge upward the forward end of the spring arm, thus raising the pin 13, out of the recess.

It is to be understood that the spring arm may be mounted in any suitable guide 6, and that it may be constructed and mounted in many other ways than that shown without departing from the spirit of my invention.

In order that the gate 11 shall be held rigidly when it has been turned from the position shown in full lines Fig. 1, to the locking position shown in dotted lines, I provide the fixed pintle 14 on which the gate is pivoted with a fixed ratchet 15, which is thus concentric with the pivotal point of the gate.

Mounted on the gate is a pawl 15' engaging with the teeth of the ratchet. The pawl and the teeth are so arranged as to permit movement of the gate from the open position

to its locked position, or continuous movement in that direction, but not to permit a reverse movement which would tend to move the gate from its closed position to the open position. Thus once the mail-bag by its supporting anchor has been received within the gate and the gate closed, it will remain closed and there is no chance for the bag to be thrown out, either through rebound or the centrifugal force due to the rotation of the arm 5.

As before stated the rear end of the arm 5 is provided with one or more shiftable counterweights 9. One weight might be fixed, this weight acting to counterbalance the standing mechanism, while the other weights can be shiftable and adjustable to counterbalance the varying weights of mail-bags.

While I do not wish to be limited to any particular manner of supporting the counterweights upon the arm 5, I have shown the arm 5 as reduced and extending through the counterweights, the counterweights being held thereon by set screws 9'. I prefer to make these counterweights slotted so as to be set on to the reduced end of the arm 5, rather than have the arm 5 pass through a passage in the counterweight, as the first construction permits me to provide the extremity of the arm 5, with a terminal stop 5" or a series of stops along its length, which will prevent the centrifugal action of the rotating arm from throwing the weights off, in spite of the set screws.

The delivering device consists of a crane or bracket formed on the vertical fixed shaft 16, the bracket piece 17 and the outwardly projecting arm 18. The shaft 16 is preferably formed so that it may be adjusted to a car door. Supported on the arm is an angular finger 19 having at the inner end thereof a sleeve 19' adapted to surround and be clamped upon the bracket arm 18, by means of the set screws 19''. As will be noted the finger is angular and its upper surface inclines downward to the point. At the bend of the finger there is a hollowed portion 19''' in which the loop of the mail-bag will rest. The finger is also provided with a spring 20 which is fastened at its inner end to the sleeve 19 and extends downward from the sleeve over the upper face of the finger to the end thereof, where it is curved upward and backward. As will be seen a space 19''' is thus left between the angle of the finger and the spring for the reception of the upper ring or eye 22 of an anchor 21. The anchor 21 is T-shaped in general form, the central depending bar having at its end the spring closed hook 21', the upper end of the central bar being formed with the transversely projecting bar 22'. At the junction of the transverse bar with the central bar of the anchor, and projecting above the same is the eye 22 adapted to slip over the finger 19.

and be supported thereon. As will be seen in Fig. 1, the mail-bag is supported at its middle within the hook 21'.

It will of course be understood that the 5 catching hook 10 and the gate 11 do not contact directly with the mail-bag itself, but engage with the depending central bar of the anchor and with the hook portion at the end of the arm 5, and that the openings of the 10 gate and of the hook 10 are both of such dimensions as will adapt them to easily receive the central bar of the anchor. The cross bar 22' prevents the anchor from dropping through or being pulled downward out 15 of the hooked end of the catcher bar 5 and the gate.

The operation of my invention is clear. As the train approaches the station the delivering arm 18 is drawn into the car and 20 the bag attached to the anchor which is placed upon the finger 19. Meanwhile the catching arm 5 has been adjusted in a direction transverse to the track with the gate 11 in its open position.

The depending anchor as it is carried along by the train enters into and strikes the gate turning the same into the position shown in dotted lines in Fig. 2, at the same time raising the locking pin 5" out of the 30 recess or notch in the upper face of the plate 3', and allowing the arm 5 carrying the bag to rotate as a whole upon the standard 2, said rotation continuing until the force of the impact has been expended. Immediately upon the closing of the gate the pawl on the end of the arm has engaged the teeth of the ratchet and the gate pivoted, thus the gate will be held in the position into which it has been moved by its contact 40 with the anchor.

It will be seen that the bag is received without any shock for the reason that the gate is turned upon its pivot by the impact of the anchor and bag, and that before it has reached the limit of its movement the latch has been raised and the arm is free to rotate. The finger 19 is not to be set exactly parallel with the line of motion of the train, but is to be inclined at a slight angle 50 to the line of motion and pointing outward from the car, so that it will approximate the line of movement of the catcher hook, thus the bag or anchor will receive no shock when the line of movement is so slightly changed.

My construction provides a lock to prevent the mail-bag from being thrown off the catching arm and also provides an anchor for the mail-bag which precludes the possibility of the bag coming in contact with any of the catching devices. This obviates one of the difficulties of ordinary catching devices in use in the majority of instances, wherein the bag itself is struck by the 60 catcher and torn away from its supports,

this action tending to rend the bag and otherwise damage it.

While I have shown what I believe to be the preferable form of my invention I do not wish to be limited thereto, as the spirit 70 thereof may be embodied in many other forms and with many modifications in detail.

Having thus described my invention what I claim as new and desire to secure by Letters Patent is:

1. A mail-bag delivering and catching mechanism comprising a supporting arm pivoted to the car for movement in a horizontal plane, a finger extending rearward at an angle to the supporting arm and a bag support 80 removably hung on said finger having means for engaging the bag and a transverse bar above said bag engaging means; in combination with catching mechanism located at the side of the track and adapted to engage with said bag support beneath said transverse bar and to withdraw it from said finger.

2. A mail-bag delivering and catching mechanism comprising a supporting arm 90 pivoted to the car for movement in a horizontal plane, a finger extending rearward at an angle to the supporting arm and a bag supporting anchor consisting of a downwardly extending rod having a bag hook at 95 its lower end, the upper end of said rod having an eye and a transverse bar formed therewith below the eye, said eye being adapted to receive the finger of the supporting arm; in combination with receiving 100 mechanism located at the side of the track and adapted to engage said anchor beneath the transverse bar and withdraw it from said finger.

3. A mail-bag catcher including a standard, an arm rotatably mounted on the standard for movement in a horizontal plane around the standard as a center, said arm having a receiving hook formed at one end and a U-shaped gate pivoted at its corner to one end of the arm so that when in one position the opening of the gate shall be in the same direction as the opening of said hook, and that when in its closed position, the sides 110 of said opening shall lie transverse to the hook, one of said sides closing the same.

4. A mail-bag catcher including a standard, an arm rotatably mounted on the standard for movement in a horizontal plane, said arm having a receiving hook formed at one 120 end; in combination with a gate pivoted to the end of the arm and adapted to be closed across said hook by engagement with a mail-bag support, and ratchet mechanism holding the gate from reverse movement after it has 125 turned to its closed position.

5. A mail-bag catcher including a standard, an arm rotatably mounted on the standard for movement in a horizontal plane, said arm having a receiving hook formed on one 130

end thereof; in combination with a gate pivoted to the end of the arm at one side of said hook, said gate being adapted to be turned from its open to its closed position 5 across said hook by contacting with a bag support, the fixed pivot of said gate being formed with a ratchet wheel thereon, and said gate being provided with a pawl engaging with said ratchet whereby said gate 10 shall be held in its closed position.

6. A mail-bag catcher including a standard, an arm rotatably mounted on the standard for movement in a horizontal plane, said arm having a receiving hook formed at 15 one end thereof, a rotatable element normally lying across the opening of said hook, but adapted to be moved to another position by engagement with a bag support, a locking bar mounted on the top of the supporting arm and carrying a pin adapted to engage with a recess formed in the upper end of said standard to hold the supporting arm from movement, said rotating element on the end of the arm being adapted to engage 20 with said locking bar to raise the pin whereby the catching arm may be rotated.

7. A mail-bag catcher including a standard, an arm rotatably mounted on the standard for movement in a horizontal plane, 30 said arm having a receiving hook at one end thereof, a rotatable element normally lying across said hook but adapted to be moved in a position parallel with said hook by engagement with a bag support, and a resilient 35 locking bar mounted on the top of the supporting arm and carrying a pin adapted to engage with a recess formed in the upper end of said standard to hold the supporting arm from movement, said rotating element 40 being adapted to wedge beneath the outer end of said resilient bar to raise the same, and with it the pin from engagement with the recess in the standard.

8. A mail-bag catching mechanism including a standard, a catcher arm rotatably mounted upon the standard and projecting on either side beyond the same, said catcher arm provided at one end with mechanism for catching and holding the mail bag, and 45 at the other end with adjustable counterweights adapted to counterbalance the mechanism and said mail-bag, said standard having a race-way formed in its upper face and balls located in said race-way supporting the said catcher arm.

9. A mail-bag catching mechanism including a standard, a catcher arm rotatably mounted upon the standard and provided at its end with mechanism for engaging and 50 holding the mail-bag, said arm having a ball-bearing upon the upper face of the

standard, the rear end of said arm being provided with adjustable and removable counterweights.

10. A mail-bag catching mechanism including a standard having race-ways formed on the upper surface of its top plate, a catcher arm mounted upon the upper face of the standard and provided with race-ways on its under face, anti-friction rollers 65 mounted within the race-ways, a bolt passing through the upper end of the standard and through the catcher arm, a washer mounted on the bolt, nuts for clamping the washer against the arm and anti-friction devices located between the washer and the 70 upper face of the arm.

11. A mail-bag catcher including a standard having a hollow portion formed at its upper end provided with a bearing plate, an 80 arm mounted upon the bearing plate provided at one end with a bag receiving hook and at the other end with adjustable counterweights, a pivot bolt passing through the bearing plate and said catcher arm around 85 which the arm rotates, anti-friction devices between the lower face of the arm and the upper face of the plate, a gate mounted on the forward end of the arm adapted to close the bag receiving hook on the end of the 90 arm, and a locking device operated by the gate having a downwardly projecting pin normally engaging with a recess formed in the upper face of the bearing plate to prevent the rotation of the catcher arm on the 95 standard.

12. A mail-bag catcher including a standard, an arm rotatably mounted on the standard for movement in a horizontal plane, said arm having a receiving hook at one end 100 thereof and the outer arm of the hook being outwardly curved, a U-shaped gate pivotally mounted upon the end of the arm, the opening of said gate coinciding with the opening of the hook under normal conditions but said gate being adapted to be turned across said hook opening by the entry of a mail-bag support therein, a ratchet for preventing reverse movement of said gate, and means for normally holding the 105 arm from rotation upon the standard, said means being thrown out of engagement upon the actuation of said gate to permit the arm to rotate.

In testimony whereof I have signed my 110 name to this specification in the presence of two subscribing witnesses.
